UNITED STATES PATENT OFFICE

2,018,085

METHOD OF MAKING FLAT EXPANDED GRILLES

Otho M. Otte, Tarentum, Pa., assignor to Allegheny Steel Company, a corporation of Pennsylvania

Application May 29, 1934, Serial No. 728,060

5 Claims. (Cl. 29—160)

This invention relates broadly to the art of metal working and more especially to methods of making metal grilles.

Grilles made from sheet metal are now used 5 for coverings for radiators, coverings for ventilator openings, coverings for doors and for windows and in fact, for many uses.

Grilles made from sheet metal such as stainless steel sheet metal, from Monel metal and from 10 stainless alloys of the group of which Allegheny metal is an example, are now used to a considerable extent. In making the grilles from such sheet metal, the desired pattern or openwork structure is obtained by punching out the portions forming the interstices or voids, therefore, 15 in order to make a grille of a certain size, a metal sheet of the same size is required and the punched out portions are scrap material. Grilles, therefore, made in this manner are of necessity more 20 or less expensive.

It has been proposed to utilize metal grilles or lattice structures for refrigerator shelving to take the place of wire rod shelving as now used.

In making such grilles for refrigerator shelving, it has been proposed to expand mild steel 25 sheet-like material; to roll the same flat after the expanding step is completed and then to form the same into a shelf structure; then to galvanize or otherwise plate such shelf structure. It 30 has also been suggested as desirable to utilize stainless steel or some other not easily corrodible metal to form such expanded metal shelving. So far as I am aware, no satisfactory way or method 35 of making such expanded grilles for refrigerator shelving or the like has been devised.

Expanded grilles made from ordinary steel, when galvanized, tinned or otherwise coated, are unsatisfactory for use in refrigerators because of their tendency to corrode.

40 An object of this invention is to provide a method of making relatively cheap openwork grilles or lattice structures from sheet metal of the type known as stainless steel, from alloys of the groups of which Allegheny metal is an example and from metals such as Monel metal. Most 45 of these metals are difficult to work, because of the fact that they are "work hardening"; others are difficult to work because of other characteristics.

50 It is necessary that grilles for such use be flat, in other words, that the bars or strips bounding the interstices or voids of the grille all lie in the same plane.

In making expanded metal by the now stand- 55 ard methods, the bars or strips bounding the in-

terstices lie in at least two different planes angularly disposed one to the other. In order to flatten such material, it is necessary to press or roll down the upstanding portions, and when this is done with "work hardening" material, it is more than likely to fracture or crack at the points of bending.

An example of an expanded metal grille or lattice structure with the bars or strips bounding the interstices or voids lying in different angularly disposed planes such as before referred to is illustrated in White Patent No. 821,843 of May 29, 1906. It will be obvious that such a structure is unsuited for use where a flat grille, (that is, one in which it is necessary to have the 15 bars or strips bounding the interstices in the same plane) is necessary as in the case of refrigerator shelving.

My invention contemplates a method of making cheap flat grilles from "work hardening" 20 alloys or metals such as above referred to; a method of expanding sheets of such metals in the plane of the sheet and not at an angle to the plane of the sheet as disclosed in said White patent.

In the drawings, I have illustrated a number 25 of forms of grille structures which can be readily made by my method from sheets of "work hardening" alloys and other metals which are difficult to work because of other characteristics.

Figure 1 schematically depicts the corrugating 30 of a metal sheet forming a step in my method; Fig. 2 illustrates the sheet after the corrugating step is finished;

Fig. 3 is an edge view of the sheet of Fig. 2; 35

Fig. 4 depicts the partially expanded sheet;

Fig. 5 is a plan view of a shelf comprising in its make-up a sheet expanded in accordance with this invention;

Fig. 6 is an enlarged view illustrating a corner 40 of the frame structure shown in Fig. 5;

Fig. 7 shows one way of bending up a strip of metal to form the frame of Figs. 5 and 6.

Fig. 8 illustrates a still further way of forming 45 the frame structure for the shelf of Fig. 5;

Fig. 9 illustrates a metal sheet before corrugating but punched in a manner for producing a grille in accordance with this invention;

Fig. 10 is an end elevation of the punched sheet 50 shown in Fig. 9 after the same is corrugated;

Fig. 11 is a view showing the partially expanded 55 corrugated sheet of Figs. 9 and 10;

Fig. 12 illustrates a portion of a sheet having 60 elongated and shaped slots therein suitable for use in carrying out this invention;

Fig. 13 is an end view of the sheet shown in Fig. 12 after corrugating;

Fig. 14 illustrates the corrugated punched sheet of Figs. 12 and 13 which has been partially expanded in accordance with this invention;

Fig. 15 schematically depicts a set of tools by means of which the method of this invention may be carried out;

Fig. 15a illustrates a portion of the set of tools 10 illustrated in Fig. 15;

Fig. 16 is a schematic view of a shear blade such as used when making the form of grille shown in Figs. 4, 5, 17, 18, and 19;

Fig. 17 is a schematic view in top plan of a 15 corrugated sheet and shows by dotted lines an expanded portion of the sheet and part of the mechanism for performing the expanding operation;

Fig. 18 is a view in perspective of certain of the 20 tools utilized in carrying out my method and includes part of a corrugated sheet ready to be expanded;

Fig. 19 is an enlarged fragmentary view in perspective of a portion of the sheet shown in Fig. 25 18; and

Fig. 20 is a diagram of my method of expanding sheet metal in the plane of the sheet without lengthwise stretching of the bounding members of the grille structure.

30 In practicing my method, a metal sheet is provided with corrugations extending in the direction in which the sheet is to be expanded and these corrugations are so positioned that one such corrugation passes through that part of the sheet 35 from which one series of bars or strips for bounding the interstices are to be sheared.

In all the forms of grille made in accordance with this invention, I prefer to punch the sheet 40 preferably by means of circular punches to provide round holes which will lie at the junctures of all of the bars or strips bounding the interstices. These round holes located at the junction points of such bars, provide narrowed sections which provide points of bending.

45 In several of the forms, instead of punching circular holes and then slitting, I punch out certain regularly spaced more or less narrow sections, each having rounded ends; each such section extending the full length of two bounding bars plus 50 the distance between the adjacent ends of such bars.

Where merely the circular holes are punched, the sheets are slit between certain pairs of these holes; in such case the sheet is corrugated before 55 the holes are punched. Where, however, in the forms in which narrow elongated sections are punched out, the punching is done while the sheet is still flat and the sheet is later corrugated. The corrugations in both cases, however, are regularly spaced and are laid out so as to come opposite each series of bars.

60 The corrugations in both instances provide the necessary extra length to the bars or strips in order that the metal may be opened up or expanded and flattened without stretching the bars or strips lengthwise.

In the opening up operation, which is a step-by-step operation, the metal is merely forced into place by flattening the corrugated parts of the 65 bounding bars or strips into the plane of the flat portion of the sheet.

The sheets from which the grilles are to be formed are preferably corrugated with the corrugations running at right angles to the direction 70 in which the sheets are rolled so that the shear-

ing of the sheets for the expanding operation is with the grain.

The sheets are preferably corrugated by means of rolls of such a diameter that but one corrugation is formed at a time. For grilles such as I have illustrated in the drawings in which the more or less diamond shaped interstices are approximately $1\frac{1}{2} \times 9\frac{1}{4}$ " rolls of approximately 24" 5 in diameter will permit the forming of one corrugation at a time. In other words, rolls of this 10 diameter will permit the pulling in of the sheet between the rolls to provide the necessary stock for each corrugation without overstretching the metal.

The drawings are all more or less schematic. In 15 Fig. 1 I have indicated the corrugating of a metal sheet 20 in the manner above indicated by corrugating rolls 21 and 22.

Fig. 2 illustrates by full lines the sheet after the corrugating step is finished. The dotted rec- 20 tangular portions 23 and 24 represent the amount the sheet is shortened in the corrugating operation.

Fig. 3 is an edge view of the sheet of Fig. 2 showing the corrugations. 25

Fig. 4 represents the partially expanded sheet. In this view, I have illustrated the manner of punching a sheet by circular punches after corrugating, to provide circular holes 25. Dotted lines 26 and 27 indicate the shear lines or the 30 shearing of the sheet between certain pairs of these circular holes 25. A portion of the sheet is shown as expanded.

In this portion, the series of bounding members or strips 28 are in line with corrugations a 35 of the sheet while bounding members 29 are in line with corrugations b.

The corrugations provide the necessary extra length to the arms 28 and 29, etc., so that as the sheet is slit and expanded, the bounding members 40 or strips 28, 29, etc., can be moved to their final position in the grille structure without the necessity of stretching the same lengthwise. When the sheet is slit as illustrated, the circular punched holes 25 occasion the formation of relatively narrow necks 30 which in the expanding operation act as readily bendable sections, that is, sections which are readily bendable in the 45 plane of the sheet.

It will be seen that when forming the grille 50 illustrated in Fig. 4, the only scrap metal is that which is punched out by the circular punches.

I find that refrigerator shelves utilizing grilles such as shown in the expanded part of Fig. 4 can be made from sheet metal such as stainless steel, 55 Allegheny metal and Monel metal at relatively small cost.

Such a shelf is illustrated in Fig. 5 and is made up of a frame having an outer or bordering portion 31, an inner support portion 32 having its 60 upper surface offset below the upper surface of the outer or bordering portion in an amount equal to the thickness of the grille. The grille member forms the support surface of the shelf and the grille is preferably spot welded in position on portion 32 of the frame structure.

Fig. 6 is an enlarged view illustrating a corner of the frame structure shown in Fig. 5.

Fig. 7 shows one way of bending up a strip of 70 suitable metal to form the frame of Figs. 5 and 6. In this view, the grille is represented by c.

In Fig. 8, I have illustrated another way of forming up the frame structure from a strip of suitable metal. 31a represents the bordering 75

portion of the frame and 32a the inner or support portion. The grille is again represented by c.

In Fig. 9, I have illustrated a metal sheet before corrugating, but punched in a manner for the production of the grille structure illustrated in Fig. 11. Instead of slitting the sheet as is done when making the grille structure of Figs. 4 and 5, the punches are formed so as to punch out from the sheet relatively long narrow sections such as 33. These are staggered with one half sections 34 and full sections 35. Circular holes 36 are also punched in order to carry out the design of grille structure shown in Fig. 11.

Fig. 10 is an end elevation of the punched sheet shown in Fig. 9, after the same is corrugated and Fig. 11 is a view showing the partially expanded corrugated sheet of Figs. 9 and 10.

It will be seen that the corrugations d come in line with bounding members 37 while corrugations e come in line with bounding members 38.

The rounded ends 33a together with the enlargements 33b provide bendable portions 39 which facilitate the opening out or expanding of the sheet to form the grille structure.

In Fig. 12 I show a portion of a sheet having the elongated and shaped slots 40 punched therein in staggered relation similar to those shown in Fig. 11. In this view, I have indicated by dotted lines x the center line of the corrugations to be formed after the sheet is punched.

Figure 13 is an end view of that portion of the sheet shown in Fig. 12, after corrugating. This view illustrates the foreshortening of the sheet by the corrugating step.

Fig. 14 illustrates the corrugated punched sheet of Figs. 12 and 13 which has been expanded or opened up except for the last two rows of the punched portion.

Since this application is primarily directed to my novel method of making the same, I have not attempted to completely illustrate any organized apparatus or machine for practicing my method or producing the product in question.

Since a machine for carrying out the method may take numerous forms, I have merely illustrated what might be termed a set of tools which may be used in a machine of any desired construction and which may be used for carrying out the various steps of my method, when properly manipulated and timed.

In Fig. 15, I have schematically illustrated such a set of tools by means of which my method may be carried out.

Figure 15a constitutes a portion of the set of tools illustrated in Fig. 15, but is a repetition of part of Fig. 15 for the sake of clearness. This view includes an additional element not shown in Fig. 15.

In Fig. 15, the corrugated sheet of the grille of Figs. 4 and 5 is shown at 41. This is shown resting upon a support table 42. At the back of the support table, is a pushing device 43 and the mechanism for operating the same will be so constructed that the pusher 43 will move in the direction of arrow 44 in a step-by-step manner so as to feed at each step sheet 41 forward on table 42 a distance corresponding to the width of the bounding bars 28-29 of Fig. 4.

A pusher device 45 located at one side of the table will have an intermittent reciprocating movement in an amount equal to one half the length of an interstice; in other words, one half of a sheet bounded by bounding members 28 and 29. The opposite side of the support table will

be provided with a similar pusher device. The support table 42 has its upper surface grooved with the grooves corresponding to and of the same spacing as the corrugations in sheet 41. The corrugations of the sheet depend into the grooves in the support table.

In order that pushing device 45 and its companion may operate to periodically shift the sheet laterally of the support table and then back to position, a series of lifting fingers 46 is provided. These are arranged at regularly spaced intervals throughout the extent of the support table 42 and work freely in the vertical bores provided for that purpose in the support table. These pins are provided at their bottoms with disk-like heads 47 and are normally held in depressed position so that their upper ends lie below the support surface of the table. This is accomplished by means of coil springs 48 which surround the pins and lie between the disk-like heads 47 and the end 49 of enlarged bores 50.

A series of rock shafts 51 having cams 52 is provided for periodically raising pins 46. This is for the purpose of raising sheet 41 so that the corrugations in the sheet will clear the grooves in the table. This allows the sheet to be moved back and forth laterally on the table. Some other means may be utilized if desired for periodically raising the sheet when it is desired to shift the same laterally.

A punch 53 (which represents one of a series extending at spaced intervals across the entire sheet) is provided and carried by a carrier member 54 which is arranged for periodical reciprocation above the support table 42. This punch operates in conjunction with a die block 55 which is let into the support table and which has a circular bore for reception of the series of punches 53.

A carrier member 56 mounted for vertical reciprocation alongside of support member 54 carries, adjacent its lower end, a series of stripper fingers 57. These fingers straddle punches 53 and are adapted to hold the sheet down when the punches are raised after punching the holes.

Adjacent the forward end of support table 42 is a lower stationary shear blade, and mounted for reciprocation above the support table is a shear blade 59. This latter blade is carried by a blade holder 60. The blade is preferably formed as shown in Figs. 16 and 18 with portions 61 more or less conforming to the corrugations in the sheet and with a central portion 62 which is bowed downwardly for the purpose of facilitating shearing and the downward displacement of the sheared portion of the sheet. It will be understood that such a shear blade is used when making grilles such as shown in Figs. 4, 5, 17, 18 and 19.

When making grilles such as shown in Figs. 9-14 inclusive no shearing will be necessary and for the upper shear blade a blunt displacer member will be substituted which will merely have the function of moving down below the plane of the sheet supported on the support table 42 the portions which have been segregated from the sheet by the punching of the long narrow portions 34, 35 and 40 (Figs. 9-12 inclusive). The downward displacement of this portion will be in an amount equal to that displaced by shear blades 59 and is merely for the purpose of placing the potential bounding members in position to be engaged by the pull out devices to be later described.

Lying in front of blade holder 60 is a presser

foot 63 having the major portion of its under surface smooth and in the plane of the upper surface of the sheet. Below this presser foot which is grooved out as shown by dotted line 64 for a purpose hereinafter to be described is a presser block 65 which is mounted so as to have an upward movement relative to the plane of the under side of the flattened sheet and a forward movement as indicated by dotted line 65a. The presser block 65 as shown in Fig. 18 is grooved to receive a vertically extending support block 66. The grooves are indicated by dotted lines 67-68 in Fig. 18. The upper surface of the support block 66 is beveled as shown at 69. Extending into each opening 70 of presser block 65 is a horizontally reciprocating rod or bar 71. The inner end of this bar is provided with a depending section 72 the under side of which is beveled as shown at 73 to correspond to the bevel 69 formed on the top of block 66. From this it will be seen that as bars 71 are reciprocated, they will be raised and lowered vertically because of these cooperating beveled surfaces 69 and 73. Each bar 71 at its forward end is provided with an upstanding hook-like portion 74.

Fig. 16 is a schematic view of a shear blade such as used when making the form of grille shown in Figs. 4, 5, and 17.

Fig. 17 is a schematic view and shows in top plan and by dotted lines a corrugated sheet in which three rows of circular holes have been punched. Part of the sheet has been expanded and the hooks 74 of the two reciprocating rods or bars 71 are shown in position ready to open up and form the next row of bounding members; the partially expanded or opened up sheet is shown by dotted lines in this view.

One roller 75 of a series forming a roller table is shown beneath the expanded part of sheet 41 in Fig. 15.

In forming a grille such as shown in Figs. 4 and 5, sheet 41 is first corrugated, it is then placed on support table 42 with the corrugations extending down into the grooves on the support table. Pusher member 43 is lined up so as to abut against the rear edge of sheet 41. Side pusher 45 is lined up so as to abut against its side of sheet 41. The forward edge of sheet 41 will extend beyond the row of punches 53 an amount equal to the width of the bounding bars 28 and 29 (Figs. 4 and 5).

It will be seen that the series of tools above described comprises a sheet support table, means for raising the sheet from the table so that the same may be reciprocated back and forth laterally; a pusher for advancing the sheet one step at a time, a series of punches forming a gang punch; a series of strippers straddling the punches of the gang and extending across above the sheet from side to side; a hold down bar arranged to clamp the sheet in position on the lower stationary knife blade; a shear knife which is reciprocated to shear the sheet and move the sheared portion down a distance below the plane of the sheet; a presser foot and a presser block for flattening out the corrugations of the severed portions and puller bars for opening up or expanding sheared off portions of the sheet.

These several tools will be timed so that after a certain number of lines of holes have been punched, say three lines (the pushers 43 and 45 having been operated in the meantime to properly position the sheet for punching) and the sheet reaches the position to be sheared it will be clamped in position between clamp bar 56 and stationary knife blade 58. As the upper

blades are retracted after the first shearing operation, hold down bar 56 is raised and the pusher member 43 advances the sheet the proper distance for the next shearing operation. Kick up pins 46 are then operated to raise the sheet clear of the grooves of the table 42, and side pusher member 45 moves the sheet sidewise for the next punching and shearing operation. The forward and sidewise movement of the sheet occasioned by means of pushers 43 and 45 so positions the sheet that the sheared off portions which now lie below the normal plane of the sheet as shown in Figs. 18 and 19 lie in front of hooks 74 of puller bars 71.

The hold down bar next descends and clamps the sheet between the lower stationary knife blade 58 and the bottom of the hold down bar. The gang punch descends and punches a new series of holes and the pull out bars 71 immediately operate to expand the cut off portions of the sheet, while the sheet is clamped in position by the hold down bar, and by the punches.

In the expanding operation, it will be understood that the puller bars are raised by the inclined surfaces before referred to and to accommodate this raising of the puller bars the under surface of presser foot 63 is grooved as shown at 64 so that the hook 74 on the end of the puller bars may move back through these grooves.

Simultaneously with the expanding movement of puller bars 71, presser block 65 rises and moves forward to flatten out the corrugations in the sheared off portions of the sheet or in other words in the potential bounding members.

Presser foot 63 while it is substantially flat on its under surface except for groove 64, preferably has a slight curvature from its forward to its rear end. This bar will be suspended on about a 20' radius so that it can swing forward as presser block 65 moves forward and upward to flatten out the portions of the sheet lying therebetween.

After the opening up or expanding and flattening operations of the severed portions have been accomplished, the presser block 65 recedes to normal position, that is, it moves angularly downward; pull out bars 71 return to normal position against the stationary knife blades 58; the gang punch is raised and hold down bar 56 is raised and pusher 43 advances the sheet one step; the kick out pins then raise the sheet free from the table and the proper side pusher then moves the sheet laterally the desired distance for the next cycle of operation.

In Fig. 20 I have attempted to schematically show my method of expanding sheet metal in the plane of the sheet without lengthwise stretching of the bounding members of the grille structure. I have assumed that I am forming a grille structure having more or less diamond shaped interstices which are $2\frac{1}{8}$ " long x $1\frac{1}{8}$ " wide. It will be seen that when the expansion takes place to open up the metal $1\frac{1}{8}$ " of an inch wide each arm forming the diamond boundary has a length of $1\frac{1}{8}$ " while the same length is maintained in the diamond as was the length sheared of $2\frac{1}{8}$ ". Therefore, the metal provided by corrugating the sheet has furnished $\frac{1}{4}$ " additional metal which allows forming the diamond in the opening-up process without stretching the metal the $\frac{1}{4}$ " increased length as shown.

Having thus described my invention, what I claim as new and desire to secure by Letters Patent is:

1. In the method of making an expanded metal

grille in which the upper surfaces of the bars bounding its interstices lie in a common plane, the steps consisting in forming corrugations in a metal sheet or strip which corrugations extend in the direction in which the material is to be expanded, in slitting the material at spaced positions with the slits extending at right angles to the corrugations and then in expanding or pulling out the slit portions of the material and during such pulling out procedure in flattening the corrugated parts of such slit off portions into the plane of the original strip or sheet.

2. In the method of making an expanded metal grille, the steps consisting in forming corrugations in a metal sheet-like member and extending in the direction in which the material is to be expanded, in punching a series of spaced holes in line across the sheet and between such corrugations, in slitting the material through such corrugations and between certain pairs of such punched holes, in pulling out the slit portions and while carrying on such pulling out procedure in flattening the corrugated parts of the slit off portions into the original plane of the sheet.

3. In making an expanded metal grille from a sheet metal blank having staggered portions which are severed from the blank except at their ends and center and corrugations which extend in the direction in which the expansion is to occur and at right angles to the major axes of such severed portions, the steps which consist in progressively expanding the corrugated blank and simultaneously with such expanding procedure in flattening the corrugated parts of the expanded severed portions so that the completely ex-

panded structure is flat and with the upper surfaces of all of its parts lying in one common plane.

4. In making an expanded metal grille from a sheet metal blank having staggered portions which are severed from the blank except at their ends and center and corrugations which extend in the direction in which the expansion is to occur and at right angles to the major axes of such severed portions, the steps consisting in expanding one row of such severed portions at a time and simultaneously with such expanding procedure in flattening the corrugated parts of such severed portions so that the expanded part is flat and with the upper surfaces of all its parts lying in one common plane; such plane being the plane of the uncorrugated parts of the blank.

5. In a method of making an expanded metal grille having regularly spaced interstices and with the upper surfaces of the members bounding such interstices lying in a common plane, the steps which consist in punching from a sheet metal blank regularly spaced portions to form a flat reticulated structure, in corrugating such structure with the corrugations intercepting the bounding members of the reticulations and then in expanding the reticulated blank in the direction in which the corrugations extend and simultaneously with such expanding procedure, in flattening the corrugated portions whereby an expanded metal blank is formed in which the bounding members for the interstices are all flat and with their upper surfaces in one common plane.

OTHO M. OTTE. 25
